THREADING DEVICES

Ludwig Meissler, Kaiserslautern (Pfalz), Germany, assignor to G. M. Pfaff A.-G., Kaiserslautern (Pfalz), Germany

Application February 9, 1953, Serial No. 335,723

Claims priority, application Germany June 30, 1952

4 Claims. (Cl. 112—225)

This invention relates to threading devices for sewing machines and is more particularly concerned with an improvement of the threading devices covered by United States Patent No. 2,704,526 assigned to the same assignee.

In the threading device in accordance with said previous application, the engagement element, which is secured to the guiding bar of the threader, for example, a pin which during operation of the threader engages a plane on the needle bar socket or on a ring member secured to the needle bar, is guided in a groove which is either defined by the needle bar rod and a disk or is formed in the ring member.

In one embodiment of that invention the accurate position of the engagement element when contacting the engagement plane is insured by a pressure spring which is disposed around the guiding bar between a lower bearing on the sewing machine head and the clamp member which carries the threading hook.

In the embodiment referred to the spring is visible and readily accessible between the head portion of the sewing machine and the clamp member. That is a disadvantage, not only as far as appearance and possible soiling are concerned, but also with respect to the assembly of the threader.

It is, therefore, the object of the present invention to improve the arrangement in accordance with the said disclosure by employing novel means in place of the said spring. For that purpose the needle bar oscillator is provided with guiding means for the engagement member. In this manner it is avoided that during downward movement the guiding bar of the threading device turns and that possibly the threading hook knocks against the needle clamp.

The guiding means is advantageously in the form of a plane surface which is aligned with the oblique plane on the ring member upon the needle bar or, in another embodiment on the disk above the needle bar socket.

An illustrative embodiment of the invention is shown in the accompanying drawing in which

Fig. 1 is a perspective view of the device in accordance with the invention showing the device in inoperative position; Fig. 2 is a view of the device similar to that shown in Fig. 1, but with the guiding bar and the components for operating the same in the depressed, operative position with respect to the needle bar, and Fig. 3 is a perspective view of the upper end portion of the device showing the end of the guiding bar projecting through the sliding member.

The perspective illustration clearly indicates the needle bar oscillator 52, the needle bar 61, the needle bar socket 17, the ring member 64 and the threading arrangement. The needle bar socket 17 and the ring member 64 are rigidly affixed to the needle bar 61. The needle bar 61 with needle bar socket 17 and ring member 64 is caused to oscillate up and down in the needle bar oscillator 52 by the pitman arm arrangement well known to the man skilled in the art, the pitman arm having operative engagement with the arm 17a of the socket 17. The ring

2

member 64 presents a guiding or corresponding plane 64' adjacent the upper portion of member 64. A guiding slot 65 is formed in the member 64 adjacent to and positioned immediately below the guiding plane 64'.

5 The guide pin 15 which is rigidly mounted in and extending through the guiding or threading bar 2 of the threader rests against a guiding plane 74 of the needle bar oscillator 52 during up and down movements of the guiding bar and is thus held in the position in which it must contact the ring member 64. During the change over from the guiding plane 74 to the ring member 64 the effect of the spring around the guide bar 2 is sufficient to prevent the rotation of the guide bar 2. The guiding plane 74 extends in the same plane as the plane 64' adjacent the slot 65 of the ring member 64. The slot can also be formed between the surface of the needle bar socket 17 and a disk disposed at a suitable distance above the socket. Member 7 is mounted on guiding bar 2 and has its lower portion bearing against spring 3. A lever 20 is attached to member 7 to permit application of downward pressure thereon to move member 7 and bar 2 downwardly into threading position. Formed in member 7 is a grooved track 16. The portion of pin 15 diametrically opposed to that portion of pin 15 resting against guiding plane 74 is journaled in grooved track 16.

In operation, actuation of the threading device is commenced by application of downward pressure upon lever 20. Lever 20 pulls down member 7 which causes bar 2 to be pulled down. Downward movement of member 7 compresses spring 3. The bar 2 along with pin 15 move downward without any rotary motion. The portion of the pin 15 guiding against the guiding plane 74 moves downwardly with respect to plane 74. The opposed portion of pin 15 in track 16 remains stationary with respect to the track 16. The ring member 64, in the threading position has its plane 64' immediately adjacent the lower edge of plane 74. Plane 64' therefore is merely an extension of plane 74 and likewise permits pin 15 to move downwardly without rotary motion. Further pressure on lever 20 causes the threading hook to be aligned with the eye of the needle. At this point pin 15 drops from plane 64' into guiding slot 65, so that pin 15 is now free to rotate. The portion of pin 15 in the track 16 follows the curvature of the track 16 which imparts rotary motion to the bar 2 causing it to rotate from right to left. This rotation swings the threading hook through the eye of the needle into position for threading the needle. Release of pressure on the lever 20 restores the structure to the beginning of its operating cycle.

50 Having now fully described my invention I claim:

1. A threading device for the needle of a sewing machine of the type provided with a needle bar oscillator supported in the head of the machine, said device including a needle bar movably supported in said oscillator, a guiding bar carrying a threading hook, said guiding bar being disposed substantially parallel to and adjacent said needle bar and slidably supported in said oscillator for longitudinal movement relative to said needle bar, and operating means for said device including a guiding surface extending on said needle bar oscillator proximate said guiding bar in the direction of movement of said guiding bar, a ring member mounted on said needle bar adjacent to and below said guiding surface and presenting a guiding slot, an actuating member secured to said oscillator and a guide pin extending through said guiding bar, said pin having in inoperative position one end in sliding engagement with said guiding surface and having its other end in operative engagement with said actuating member; whereby downward pressure on said actuating member causes axial movement of said guiding bar thereby guiding said pin to said guiding slot and continued pressure causes arcuate movement of said pin in said slot thereby

imparting rotative action to said guiding bar to swing the threading hook through the eye of the needle.

2. A threading device for the needle of a sewing machine of the type provided with a needle bar oscillator supported in the head of the machine, said device including a needle bar movably supported in said oscillator, a guiding bar carrying a threading hook, said guiding bar being disposed substantially parallel to and adjacent said needle bar and slidably supported in said oscillator for longitudinal movement relative to said needle bar, and operating means for said device including guiding surface extending longitudinally of said oscillator proximate said guiding bar in the direction of movement of said guiding bar, a ring member mounted on said needle bar adjacent to and below said guiding surface and presenting a first guiding slot, an actuating member secured to said oscillator presenting a second guiding slot, and a guide pin extending through said guiding bar, said pin having in inoperative position one end in sliding engagement with said guiding surface and having its other end in operative engagement with said actuating member by way of said second slot; whereby downward pressure on said actuating member causes axial movement of said guiding bar thereby guiding said pin to said guiding slot and continued pressure causes arcuate movement of said pin in said first and in said second slot thereby imparting rotative action to said guiding bar to swing the threading hook through the eye of the needle.

3. A threading device for the needle of a sewing machine of the type provided with a needle bar oscillator supported in the head of the machine, said device including a needle bar movably supported in said oscillator, a guiding bar carrying a threading hook, said guiding bar being disposed substantially parallel to and adjacent said needle bar and slidably supported in said oscillator for longitudinal movement relative to said needle bar, and operating means for said device including a guiding surface extending longitudinally of said needle bar oscillator proximate said guiding bar in the direction of movement of said guiding bar, a ring member mounted on said needle bar adjacent to and below said guiding surface and presenting a first guiding slot, an actuating member secured to said oscillator presenting a second guiding slot, and a guide pin extending through said guiding bar, said pin having in inoperative position one end in sliding engagement with said guiding surface and having its other end in operative engagement with said actuating member

by way of said second slot and a biasing spring disposed around said needle bar and extending between said oscillator and said actuating member; whereby downward pressure on said actuating member against the force of said spring causes axial movement of said guiding bar thereby guiding said pin to said guiding slot and continued pressure causes arcuate movement of said pin in said first and in said second slot thereby imparting rotative action to said guiding bar to swing the threading hook through the eye of the needle.

- 10 4. A threading device for the needle of a sewing machine of the type provided with a needle bar oscillator supported in the head of the machine, said device including a needle bar movably supported in said oscillator, a guiding bar carrying a threading hook, said guiding bar being disposed substantially parallel to and adjacent said needle bar and slidably supported in said oscillator for longitudinal movement relative to said needle bar, and operating means for said device including a guiding surface extending longitudinally of said needle bar oscillator proximate said guiding bar in the direction of movement of said guiding bar, a ring member mounted on said needle bar adjacent to and below said guiding surface and presenting a first guiding slot, an actuating member secured to said oscillator presenting a second guiding slot, and a guide pin extending through said guiding bar, said pin having in inoperative position one end in sliding engagement with said guiding surface and having its other end in operative engagement with said actuating member
- 15 20 25 30 35 40
- by way of said second slot, a biasing spring disposed around said needle bar and extending between said oscillator and said actuating member and a manipulating lever disposed on said actuating member; whereby downward pressure on the lever of said actuating member against the force of said spring causes axial movement of said guiding bar thereby guiding said pin to said guiding slot and continued pressure causes arcuate movement of said pin in said first and in said second slot thereby imparting rotative action to said guiding bar to swing the threading hook through the eye of the needle.
